COMBINATION TABLE, AQUARIUM, AND PLANT RECEPTACLE

Lucille G. Newcome, Minneapolis, Minn.

Application March 12, 1949, Serial No. 1,371

Term of patent 7 years

(Cl. D33—14)

To all whom it may concern:

Be it known that I, Lucille G. Newcome, a citizen of the United States of America, residing at 2519 Emerson Avenue South, Minneapolis, county of Hennepin, State of Minnesota, have invented a new, original, and ornamental Design for Combination Table, Aquarium and Plant Receptacle, of which the following is a specification, reference being had to the accompanying drawing forming a part thereof, in which:

Fig. 1 is a top perspective view of a combination table, aquarium and plant receptacle, showing my new design;

Fig. 2 is a side elevation thereof; and
Fig. 3 is an end elevation of the same.

I claim:

The ornamental design for a combination table, aquarium and plant receptacle, as shown.

LUCILLE G. NEWCOME.
